Primary Examiner—M. N. Pandozzi**Attorney, Agent, or Firm—Emch, Schaffer, Schaub & Porcello Co., L.P.A.****[57] CLAIM**

The ornamental design for a stem for an article of glassware, as shown and described.

DESCRIPTION

FIG. 1 is a front elevational view of the present design; FIG. 2 is a side elevational view thereof; the opposite side elevational view being a mirror image thereof;

FIG. 3 is a rear elevational view thereof;

FIG. 4 is a top view thereof; and,

FIG. 5 is a bottom view thereof.

The broken line showing the bowl in FIG. 1 is illustrative of environmental structure only and forms no part of the claimed design.
